LAMP SOCKET

Gustaf A. Johnson, New Bedford, Mass.

Application July 6, 1931, Serial No. 548,883

5 Claims. (Cl. 173—358)

This invention relates to electric lamp sockets and is herein exemplified in that type of such devices commonly known as candle sockets.

One of the important objects of the invention is the simplification of the socket in which an insulating disk is employed for insulating the central socket terminal which disk is locked within the shell against rotation by spinning a portion of the shell around its periphery.

10 Another important object of the invention is the provision of a socket member which may be made of a uniform length adapted to be mounted upon supports of different lengths or upon an extensible support in order to fit tubular jackets of different lengths.

A further object of the invention is the provision of a socket of simplified construction with a minimum of parts, which is easily assembled and can be manufactured at a low cost.

20 Other objects of the invention will be more specifically described and pointed out hereinafter.

One of the important features of my invention consists in providing a disk of porcelain or other suitable insulating material adapted to be fitted 25 in the base of the screw shell for insulating the central socket terminal which disk is held firmly locked against rotation by spinning a portion of the screw shell around its periphery. The use of such a disk eliminates insulating parts and greatly 30 simplifies the construction and assembling of the socket.

Furthermore, by fastening to the disk a member to which a support of any length may be secured, the socket may then be adapted for supports of various lengths which constitutes another feature of my invention. This feature is of special importance in relation to candle sockets because it standardizes the socket member of such sockets which is of great advantage to the 40 manufacturer. Heretofore, the jackets used in connection with candle sockets, which jackets have simulated candles, have been of various lengths which required the manufacturer to keep on hand a stock of each length in order to fill 45 orders promptly. In order to avoid carrying a large inventory of different lengths, sockets having extensible supports have been produced, but have not proved entirely satisfactory nor have they been accepted by the trade to such an extent as to eliminate the necessity of carrying a supply of sockets with different lengths of supports. By making the socket member, that is, the screw shell and contacts, complete and providing it with a member to which may be secured 50 a support of any length, either extensible or non-

extensible, and by providing a supply of supports of various kinds, orders for specified sockets may be rapidly filled by the single operation of fastening the supports required by the order to the socket member. This obviates the necessity of 60 carrying a large stock of completed and assembled candle sockets of various lengths.

In the accompanying drawing illustrating my invention as applied to a candle socket, Figure 1 is a side elevation of a complete candle socket 65 fixture with the lamp in position; Fig. 2 is a vertical central sectional view of the fixture with the candle jacket removed showing an extensible support; Fig. 3 is a side elevation of the same looking from right to left in Fig. 2; Fig. 4 70 is a central sectional view of the shell with insulation and contacts but taken on a line perpendicular to the sectional view in Fig. 2; Fig. 5 is a bottom plan view of the shell; Fig. 6 is a top plan view of the insulating disk looking downwardly in Fig. 4; Fig. 7 is a bottom plan view 75 of the insulating disk; Fig. 8 is a plan view of the insulating member which is mounted on the bottom face of the insulating disk; Fig. 9 is a cross sectional view of the extensible support of 80 the socket on line 9—9 in Fig. 3; Fig. 10 is a side elevation of a socket member with a non-extensible support; Fig. 11 is a view in perspective of the central terminal or contact and Fig. 12 is a similar view of the shell terminal or 85 contact.

Referring to the drawing, the socket member comprises a lamp receiving screw shell 15 having mounted in its base an insulating disk 16 which may be of porcelain or any other suitable 90 insulating material. The base of the screw shell is provided with an opening 17 approximately circular to expose the outer face of the insulating disk, which opening leaves an inwardly extending flange 18 on the base of the shell and upon this flange is seated the insulating disk 16. In order to secure said disk in fixed position in the base of the shell, its periphery is rounded over on its top edge and that portion of the shell adjacent thereto is pressed or spun inwardly over said rounded surface so that the the 95 insulating disk is held firmly fixed between the flange 18 and the spun portion 19 of the shell. 100

The disk 16 (Figs. 6 and 7) is provided with a central circular opening 20 and with a rectangular recess 21 formed in its outer surface for receiving and holding the top portion of a forked member 22, said top portion having a projecting collar portion 23 adapted to enter the opening 20 in the disk and to have its end 110

turned over and riveted or screwed upon a shoulder 34 countersunk in the upper face of the disk whereby the forked member 22 is riveted to the disk. The forks or shanks of the 5 forked member are relatively short and each is provided on its end with an outwardly turned finger 25 designed for supporting and holding in place an insulating cylinder 26 interposed between the screw shell and the imitation candle 10 jacket 27.

Mounted in the disk 16 are two terminals or contacts 30 and 31, the former being a central lamp contact and the latter a shell contact. The contact 30 is in the form of an elongated flat 15 bar (Fig. 11) having threaded through one end a binding screw 32. After being inserted through an off center slot 33 in the disk, the upper end is bent over in position to make a spring contact with the lamp when inserted in the shell (Fig. 4). The 20 contact is bent flatwise to form two transverse shoulders 34 and 35, the latter of which engages a recessed shoulder 36 on the lower or outer face of the disk and the former of which is provided with a hole 37 to facilitate the bending of the 25 upper end to make the spring contact. The shoulder 36 when the upper end is bent over holds the contact in fixed position. The upper face of the disk may also be provided with a 30 rectangular recess 38 (Fig. 6) to prevent lateral movement of the upper end of the contact when the lamp is screwed into contact with it.

The contact 31 has threaded through its lower end, a binding screw 40 and the central portion of its upper end is cut and turned laterally to 35 form a square lug 41 adapted to be firmly held between the flange 18 of the shell and a projection 42 on the outer face of the disk when those parts are assembled. The two prongs 43 on the upper end of the contact engage holes 44 in the disk to lock the contact against lateral 40 movement.

A member 46 of the form shown in Fig. 8 made of thin sheet insulating material is mounted in the recessed bottom face of the disk 16 to insulate 45 the forked member from the contacts and the four extended corners 47 of the insulating member project in between the disk and the flange of the shell to hold it in position.

In the assembling process, the forked member 50 is first riveted to the disk 16, the contacts 30 and 31 are mounted in the disk, the insulating member 46 then placed in position between the forks of said member 22 with the said contacts fitting in its rectangular end slots and the disk 55 with the above parts mounted in the shell, after which, the shell is spun around the periphery of the disk to hold all the parts in fixed position. The outer surface of the insulating member 46 and the outer surfaces of the three projections 60 48 all lie in the same plane and engage the flange 18 of the shell when the latter is spun around the periphery of the disk.

The socket member, therefore, comprises the screw shell, insulating members and contacts and the forked member and in this condition constitutes a standard part as shown in Fig. 4 which may be mounted either on an extensible support or a non-extensible support of any length in order to conform to candle jackets of various lengths.

In Figs. 2 and 3, the socket member is shown mounted on an extensible support which comprises a lower forked member 50 having its lower end 51 in tubular form with an interior thread whereby it may be threaded upon the threaded part of a tubular fixture support 52 carrying

insulated conductors 54 and 55, which conductors are adapted to be carried up through the support and connected to the contacts 30 and 31 respectively. The two forks or shanks of the forked member 50 are U-shaped in cross section (Fig. 9) and slidably mounted therein are two skeleton extensible shanks 57 also U-shaped in cross section, which are adapted to slide vertically in the forks of the forked member for increasing or decreasing its length. In order to hold the extensible shanks 57 in adjustable position, a screw 58 is mounted transversely in the upper ends of the forks of the member 50, the end of the screw being threaded through one of the forks in order to draw the forks together or to separate them by the manipulation of the screw. Cooperating with the screw 58 is a transverse bar 60 having its ends reduced to form a central projecting finger 61 on each end with a shoulder on each side of the finger. The fingers project through longitudinal slots 62 in the extensible members and through holes in the forks of the forked member 50 so that when the screw is tightened the shoulders on the ends of the transverse bar hold the extensible members in locked adjustable position. 100 By releasing the screw 58 the extensible members can be moved vertically to any desired adjustment and secured therein by tightening the screw. In order to mount the socket member on the upper ends of the extensible members, the latter are provided with end recesses 63 adapted to receive the fingers 25 and the flanges of the extensible members at their upper ends are swaged around the forks of the forked member 22 thereby securing the extensible members 105 permanently to the socket member.

The non-extensible support 70 such as is shown in Fig. 10 is of somewhat similar construction to the forked member 22 being also a forked member having its lower end in the form of a 110 cylindrical threaded portion 71 to permit it to be mounted upon the threaded part of the fixture support 52. The upper ends of the forks are of the same construction as the upper ends of the extensible members 57 in Figs. 2 and 3 and 115 the flanges of said upper ends are swaged about the shanks of the forked member 22 in order to secure the member 70 permanently to a socket member. Since the various sizes of candle jackets are standard, the manufacturers by having a 120 supply of non-extensible supports of various standard lengths may, by attaching supports of the proper length, complete candle sockets within a very short time for delivery to fill an order for 125 sockets of specified length.

In Fig. 1 is shown an electric light fixture in imitation of a candle illustrating the use to which candle sockets are put, in which the candle socket is mounted upon the fixture support 52 as shown in Fig. 2 a cup-shaped member 75 being mounted 130 on the threaded portion of the supporting fixture 52. The jacket 27 simulating a candle is then mounted over the socket and is held against lateral movement by the insulating cylinder 26. When the electric lamp 76 is screwed into the 135 shell the fixture then presents the appearance shown in Fig. 1.

In this embodiment of the invention, the candle socket is shown as being of the keyless type, that is, operated at a distance from the socket 140 by a push button or other circuit closing device. My invention may, however, be applied to key or pull chain sockets by the addition of a switch mechanism to the socket mechanism, which application would be obvious to anyone skilled in 145

the art and would involve no material changes in the construction of my socket as exemplified herein.

It will be observed that the socket of my invention is of very simple construction and involves a minimum of parts and that it is easily assembled thereby enabling the socket to be manufactured at a very low cost.

It is to be understood that my invention is not to be limited to the exact construction herein shown and described since it may be embodied in other forms of construction within the scope of the following claims.

What I claim is:

1. In an electric socket, the combination of a lamp receiving screw shell having an open base and an inwardly projecting base flange, an insulating disk mounted in the base of said shell and seated on said flange, said disk being provided with a rectangular recess in its bottom face and a forked member having its head fitting in said recess and fastened to said insulating disk, said forked member having a pair of parallel short forks depending from said insulating disk and permanently fastened thereto a forked supporting member of a length suitable to the length of candle jacket with which the socket is to be used.

2. In an electric socket, the combination of a lamp receiving screw shell having an open base and an inwardly projecting base flange, an insulating disk mounted in the base of said shell and seated on said flange, said disk being tightly enclosed within the base of said shell and being provided with a rectangular recess in its bottom face and a through and through slot, a center contact mounted in said slot, a shell contact held between said disk and the flange of said shell, and a forked member having its head fitting in said recess and being riveted to said insulating disk, said forked member having a pair of parallel short forks depending from said insulating disk and permanently fastened thereto a forked supporting member of a length suitable to the length of candle jacket with which the socket is to be used.

3. In an electric socket, the combination of a lamp receiving screw shell having an open base and an inwardly projecting base flange, a relatively thick insulating disk fixed in the base of said shell and seated on said flange, said disk

being provided with a rectangular recess in its bottom face and a forked member having its head fitting in said recess and fastened to said insulating disk, said forked member having a pair of parallel short forks depending from said insulating disk and having each a laterally turned end finger and permanently fastened thereto a forked supporting member of a length suitable to the length of candle jacket with which the socket is to be used, each of the forks of said supporting member having an end recess for engaging a finger on one of said short forks when fastened thereto.

4. In an electric socket, the combination of a lamp receiving screw shell having an open base and an inwardly projecting base flange, a porcelain insulating disk mounted in the base of said shell and seated on said flange, said shell tightly enclosing said disk and said disk being provided with a rectangular recess in its bottom face, a forked member having its head fitting in said recess and riveted to said insulating disk, said forked member having a pair of parallel short forks depending from said insulating disk, each of said forks having an outwardly turned finger on its lower end, and a forked supporting member comprising a pair of parallel forks connected at their lower ends by a collar having an interior thread, each of said forks having its upper end provided with a rectangular open recess and being permanently fastened to one of the forks of said first-mentioned forked member with a finger on said forked member seated in said recess.

5. In an electric socket, the combination of a lamp receiving screw shell having an open base and an inwardly projecting base flange, an insulating disk mounted in the base of said shell and seated on said flange, said disk being provided with a rectangular recess in its bottom face, a forked member having its head fitting in said recess and fastened to said insulating disk, said forked member having a pair of parallel short forks depending from said insulating disk and an extensible support, said support comprising a pair of parallel shanks, U-shaped in cross-section and each being permanently fastened at one end to one of said short forks and a forked member adjustably mounted on said shanks in telescopic relation therewith.
